Application March 16, 1939, Serial No. 262,140

8 Claims. (Cl. 46—86)

This invention relates to toys, and particularly to aerial toys of the type in which a projectile shaped to conform to the figure of a man is provided with a folded enclosed parachute attached thereto, and having mechanism expected to release the parachute following the shooting or impelling of the projectile upwardly into the air.

Heretofore various expedients for releasing the parachute of a toy of this character have been proposed, consisting chiefly of gravity actuated devices, but which have been found in practice to be unreliable for this purpose.

The primary object of this invention is to provide reliable means, simple in operation, for positively releasing the aforesaid parachute when the projectile reaches substantially the top of its flight. A further object of the invention is to provide a toy that will closely approximate in a realistic manner the standard practice employed by aviators in folding and enclosing a parachute, and the freeing of same by releasing the usual surrounding flaps of the enclosure.

The invention consists of parachute-controlling mechanism adapted to be cocked, or set, before the projectile is fired, as by any suitable means not shown, and to be automatically tripped through forces of inertia generated by the sudden start of the flight, but the timing of the mechanism being such as to provide a definite interval, or lag, before certain parts thereof can reach a position effective to liberate the parachute, so that it may then be free to open and allow the toy to descend slowly.

The invention will be better understood from the embodiment shown and described herein, reference being had to the accompanying drawing forming a part hereof, in which:

Figure 1 is a perspective view of the toy of this invention with the contained mechanism in a set position ready for the flight of the device.

Figure 2 is an elevation, partly in section, of the parachute-controlling mechanism removed from the toy, and shown in a cocked, or set position.

Figure 3 is a similar view but showing the mechanism in the position assumed to release the parachute.

Figure 4 is an enlarged vertical central section of the device shown in Figure 1, with the parachute omitted.

Figure 5 is an enlarged side elevation of the mechanism of Figure 2, as viewed from the right, and.

Figure 6 is an elevation of the toy as it appears descending with the parachute opened.

In the drawing, 10 represents the figure of a

man, and 11 his head. The back 12 is cut away to form a rectilinear recess 13, open rearwardly and on top, for the reception of the parachute-controlling mechanism shown in Figures 2, 3, 4 and 5. The latter is mounted on a rectangular plate 14, having cylindrical spacers 15 attached thereto, and tapped to receive screws 16, which pass through the body of the man from the front thereof and securely clamp the plate 14 in such a manner that it will form an outer or rear wall 10 for the recess 13, and thus provide a protective housing within which the mechanism will be hidden.

A casing 17, preferably made of cloth, is provided to enclose a parachute 18 which has shrouds 19 meeting at a common point and joined to a short cord 20 for attachment to a screw eye 21 secured in the top of the head 11. The casing is provided with side flaps 22—22, a top flap 23, and a bottom flap 24, and is attached to the plate 14 as by glue or other suitable adhesives. It is reinforced by a piece of cardboard 25 glued to the inside and cut to approximately the same size as the plate 14.

A clip 26 is suitably secured to the outer end 25 of flap 24 and is adapted to engage the top edge of the plate 14, as shown in Figures 1 and 4, when the flaps are wrapped around the parachute as in Figure 1, and thus holds the parachute within the casing 17.

Mechanism is provided for lifting the clip 26 to allow the flaps to fall away and release the parachute. For this purpose there is a lever 27 pivoted on the inside of plate 14 at 28. It is twisted at one end to form a handle or finger piece 29 which projects beyond one side of the man 10, for use in cocking the mechanism, and is pivoted adjacent its other end at 30 to the bifurcated end 31 of a rod 32 having a piston 33 at its opposite end. A portion of the upper edge of lever 27, substantially midway between pivots 28 and 30, is bent to form a lug 27' which engages the surface of plate 14 to stabilize the lever, and is positioned so that it may swing into engagement with the clip 26 just before the lever reaches the position shown in Figure 3.

The piston 33 is snugly slidable in a tube 34 which is pivoted at its lower end, as at 35, to the plate 14. The upper end of the tube is closed with a plug 36 through which the rod 32 slides 50 with a running fit.

It will now be apparent that when lever 27 is moved from the position in Figure 3 to that shown in Figure 2 to cock the mechanism, air will be cushioned in the tube 34 but can pass slowly 55

beyond the piston due to the free fit of the latter in tube 34. Likewise when the movement of the mechanism occurs in a reverse direction effective to release the parachute, a slight vacuum will 5 be established below the piston thus retarding its upward movement in tube 34 commensurate with the rate at which air can again pass the piston to permit it to slowly reach the end of its upward stroke.

10 The piston 33 is moved upwardly by the urge of a spring 37 which is first compressed by the manual movement of the handle 29 during the cocking of the mechanism. Spring 37 is coiled around a rod 38 slidably mounted in a sleeve 39 15 pivoted at 40 to the plate 14. Rod 38 is secured to a bifurcated head 41 pivoted at 42 to lever 27.

Lever 27 is held in the set position shown in Figure 2 by means of a bellcrank lever 43 pivoted to plate 14 at 44, and normally urged against a 20 stop pin 45 by a spring 46 coiled around pivot 44. One end of the spring engages lever 43, and the other end is secured to plate 14 as shown in Figure 5.

Bellcrank lever 43 has an upper arm 47 and a 25 lower arm 48. Arm 47 is provided with a tooth 49 and a sloping surface 50 above the tooth, constituting latching means, the tooth being adapted for engagement with a surface 31' within the bifurcated end 31 of rod 32, and the sloping surface for engagement with the lower edge 30 of end 31 to thereby cause lever 43 to rock in a clockwise direction and effect a latching engagement of tooth 49, when the handle 29 is operated. Sufficient power will then be stored in the 35 spring 37 to operate the mechanism for the purpose set forth.

Mounted on the plate 14 are two studs 51 supporting a stationary vertical rod 52 secured at opposite ends to said studs in spaced relation to the plate. A weight 53 is loosely mounted 40 to reciprocate freely on rod 52, and is in turn supported on a light spring 54 of a strength sufficient only to counterbalance the weight when in its uppermost position as shown. Arm 48 of 45 bellcrank lever 43 projects into the path of travel of the weight 53.

When the parachute-controlling mechanism is in the set position shown in Figure 2 with the 50 parachute folded and wrapped in the casing 17, and with the clip 26 hooked over the top of plate 14 as in Figure 1, the toy is ready to be shot upwardly into the air.

Suitable means, not shown in the drawing, may be employed for this purpose, such for example, as a short board inclined at a sharp angle to the perpendicular, and having spring-means associated with a trigger; or a sling consisting of a stick to be held in one hand, and having a rubber band attached for looping under the chin of the 55 man, then grasped in the other hand, and the band stretched to impell the toy. In any event, the resulting sudden movement of the toy as it is started in an upward direction, will cause the weight 53, due to its inertia, to quickly descend 60 along the rod 52 to approximately the position shown in broken lines in Figure 2, and because of the readily yieldable character of spring 54 upon which weight 53 is poised. Lever 43 will thereupon be actuated by the engagement of the weight 65 53 with arm 48 of the lever. Arm 47 will then be moved away from the bifurcated end 31, and its tooth 49 will be disengaged therefrom. The urge of spring 37 will then swing the lever 27 in a counter clockwise direction about its pivot 28, 70 and piston 33 will consequently be drawn upward- 75

ly in tube 34, but at a relatively slow rate of speed due to the aforesaid partial vacuum maintained below the piston during such travel.

The time required for the piston to reach its outermost position is equal to approximately a 5 count of six, and corresponds to the interval of time required for the toy to reach its maximum height in the air. As the lug 27' swings upwardly with that end of lever 27, it will presently come into contact with clip 26 and elevate it out of 10 engagement with plate 14. As soon as the clip is free of the plate 14, flaps 22-22, 23 and 24 will burst open because of the resilient character of the material of which the parachute is made, such as China silk, and because the parachute is 15 folded back and forth in the conventional manner of pleating, commonly practiced by aviators.

The humanlike figure 10, although of comparatively light weight, is nevertheless very much heavier than the parachute, and will descend 20 more rapidly assuring the full opening of the parachute as it catches the air substantially as in regular practice. The mechanism as shown is timed to operate at heights of about fifty feet. Should pivot 42 be located nearer to pivot 28, the 25 timing would be slower because of the less favorable leverage therebetween, and conversely the timing would be shortened by increasing the distance between the said pivots.

It will now be seen that dependable means have 30 been provided for automatically releasing the parachute at an appropriate time that are independent of any particular inclination of the projectile in the air, and that are correlated to the beginning of its flight rather than to the end 35 thereof for operative tripping of the releasing mechanism.

It also will be obvious that such a mechanism could be applied to a regular parachute harness for use by human jumpers, or dummies frequently employed in the testing of parachutes, and in which the latching means disclosed herein could be manually tripped immediately before the jumper left an airplane, and could be timed to automatically effect the freeing of the parachute 45 at a suitable predetermined time, or for supplemental use as a safety device.

We claim:

1. In a toy to be impelled into the air and having a folded enclosed parachute attached thereto, 50 mechanism for releasing the parachute at a predetermined time during the flight of said toy, comprising a latch and a cooperating surface for holding parts of said mechanism under tension in a cocked or set position, and means for tripping said latch arranged to be movably responsive to forces of inertia generated by the sudden start of the flight of said toy.

2. In a toy to be impelled into the air and having a folded enclosed parachute attached thereto, 60 mechanism including spring means for releasing the parachute at a predetermined time during the flight of said toy, comprising a latch and a cooperating surface for normally holding parts of said mechanism against the urge of said spring means in a cocked or inactive position, means for tripping said latch arranged to be movably responsive to forces of inertia generated by the sudden start of said flight, and means for retarding the movement of said mechanism to delay the releasing of said parachute.

3. A mechanism for automatically releasing a folded parachute from an enclosing structure during the flight of same, comprising tensioning means, and latching means for normally holding 75

said mechanism under tension in a cocked or inactive position, and means effective for automatically retarding the movement of said mechanism to delay the releasing of said parachute to a predetermined extent following the tripping of said latching means.

4. A mechanism for automatically releasing a folded parachute from an enclosing structure during the flight of same, comprising tensioning means, and latching means for normally holding said mechanism under tension in a cocked or inactive position, means for automatically tripping said latching means at the beginning of said flight, and means for automatically retarding the movement of said mechanism following said tripping to delay the releasing of said parachute.

5. In a toy to be impelled into the air having a folded parachute attached thereto and a casing for enclosing same, means for securing the casing in a closed position, mechanism for automatically opening said casing to liberate said parachute at a predetermined time during the flight of said toy, effective to operatively engage said casing securing means, comprising a cylinder, a piston in same, and a piston rod, and including means for manually moving the piston rod in one direction, and spring means for moving it in the opposite direction, a latch and a cooperating surface for holding said rod and spring means against the urge of said spring means, and means for automatically tripping said latch at the beginning of the flight of said toy.

6. In a toy to be impelled into the air having a folded parachute attached thereto and a casing for enclosing same, flaps forming a part of said casing adapted to be wrapped around said parachute, a clip secured to one of said flaps and adapted to cooperate with a surface on said toy and hold all of said flaps in such closed position, mechanism for automatically releasing said flaps to liberate said parachute at a predetermined time during the flight of said toy, comprising a pivoted lever adapted to be manually rocked in one direction, spring means for moving the lever in an opposite direction to engage said clip, and adapted to be tensioned by the aforesaid initial movement of said lever, a cylinder, a piston in same, and a piston rod pivotally connected to said lever for retarding the movement of same, a latch and a cooperating surface on said mechanism adapted to hold said lever against the

urge of said spring means, and means for automatically tripping said latch at the beginning of the flight of said toy.

7. In a toy to be impelled into the air having a folded parachute attached thereto and a casing for enclosing same, flaps forming a part of said casing adapted to be wrapped around said parachute, a clip secured to one of said flaps and adapted to hold all of said flaps in such closed position, mechanism for automatically releasing said flaps to liberate said parachute at a predetermined time during the flight of said toy comprising a pivoted lever adapted to be manually rocked in one direction, spring means for moving the lever in an opposite direction to engage said clip and adapted to be tensioned by the aforesaid initial movement of said lever, a cylinder, a piston in same, and a piston rod pivotally connected to said lever for retarding the movement of same, a latch consisting of a bellcrank lever one arm of which is provided with a tooth to effect a latching engagement with a cooperating surface on said mechanism, and hold said lever against the urge of said spring means, a weight slidably mounted and adapted to engage the other arm of said bellcrank lever, a spring for supporting and counter balancing the weight, whereby when the toy is moved suddenly upward the inertia of said weight will effect its operative engagement with said bellcrank lever to rock same and disengage said tooth for the purpose set forth.

8. A mechanism for automatically releasing a folded parachute from an enclosing casing during the flight of same, comprising means for securing said casing in a closed position, means effective to operatively engage said casing securing means at a predetermined time to liberate said parachute consisting of means for tensioning said mechanism and latching means for normally holding said mechanism under tension in a cocked position, further means for tripping said latching means effective at the beginning of said flight, and means for retarding the movement of said mechanism toward said casing securing means effective to delay the releasing of said parachute following the tripping of said latching means.
